UNITED STATES PATENT OFFICE.

JESSE E. KRESKY, OF PETALUMA, CALIFORNIA.

GASEOUS-FUEL BURNER.

Application filed October 2, 1924. Serial No. 741,148.

The invention relates to that type of burner wherein the heat produced is partly utilized to change liquid fuel into vaporous fuel which is consumed at the burner fuel 5 outlet.

An object of the invention is to provide a burner which may be adjusted to fit fire boxes or other containers of different size.

Another object of the invention is to provide a high capacity burner in which there 10 is a free flow of air to all of the fuel release apertures, so that perfect combustion of the fuel occurs.

Another object of the invention is to 15 provide a vaporous fuel generating burner in which the temperature of the generator is maintained below the temperature of the flame, so that the generator will not become fouled with carbon as rapidly as do generators which are subjected to the direct action of the flame.

Another object of the invention is to provide an improved generator which may be 20 readily cleaned and which is constructed to prevent the passage of solid particles to the vapor fuel discharge outlet.

Another object of the invention is to provide a gaseous fuel burner having fuel release apertures formed to permit the release 25 of large quantities of fuel without the liability of backfire into the burner.

The invention possesses other advantageous features, some of which with the foregoing, will be set forth at length in the following description, where I shall outline in full that form of the invention which I have selected for illustration in the drawings accompanying and forming part of the present specification. In said drawings I 30 have shown one form of burner embodying my invention, but it is to be understood that I do not limit myself to such form, since the invention, as set forth in the claims, may be embodied in a plurality of forms.

40 Referring to said drawings:

Figure 1 is a plan or top view of the burner of my invention.

Figure 2 is a side elevation of the burner.

Figure 3 is an end elevation of the burner.

50 Figure 4 is a longitudinal vertical section of the burner taken on the line 4—4 of Figure 1.

Figure 5 is a cross section of the burner taken on the line 5—5 of Figure 2, and 55 showing in dotted lines the extended position of one of the fuel chambers.

Figure 6 is a top view of a portion of one of the fuel chambers, Figure 7 is a longitudinal section through one end of the generator tube, showing the fuel distributor therein. 60

The burner of my invention is particularly adapted for the consumption of a vaporous or gaseous fuel which has been produced from a liquid stock, such as kerosene, distillate and other grades of liquid fuel. The 65 liquid fuel is introduced into a generator or retort in which it is vaporized and the vaporized fuel discharges through a throat wherein it becomes mixed with air, into a mixing chamber in which a homogeneous 70 mixture of the fuel and air is produced. The resultant mixture is the combustible fuel. From the mixing chamber, the combustible mixture passes into fuel chambers provided with fuel release apertures and the 75 fuel burns at these apertures.

The burner of my invention comprises a mixing chamber 2, closed at its forward end by a wall 3 having an aperture therein in which there is disposed a longitudinally adjustable throat 4. The vaporized fuel is discharged through a nozzle toward the throat and, in entering the throat, induces a flow of air into the throat so that a mixture of air and vaporized fuel is discharged into 80 the mixing chamber. The throat 4 is provided with a bail 5 whereby its position may be longitudinally adjusted and varying the position of the throat, the proportion of air and vaporous fuel in the mixture 85 may be varied. The top and side walls of the mixing chamber 2 extend beyond the end wall 3 thereof to form a hood 6 which shields the stream of vaporous fuel discharging from the nozzle into the throat 4, so that 90 the proportions of the combustible mixture are not varied by drafts and currents of air surrounding the burner.

The mixing chamber is provided adjacent its ends with supports 7 on which the generator tube 8 is carried. Liquid fuel is introduced into the generator tube through the conduit 9 (the fuel being introduced under pressure) and is vaporized in the generator. The vaporous fuel produced in the generator, discharges therefrom through the conduit 12 which depends vertically from the tube 8 at the end thereof, remote from the fuel inlet conduit. The conduit 12 is provided with a discharge nozzle 13 which is 100 substantially axially aligned with the throat 4 and the flow of vaporous fuel through this

nozzle is controlled by a needle valve 14. The needle valve is provided on its end with a thin blade 15 extending through the aperture in the nozzle, so that in the event the aperture becomes plugged with solid material, the rotation of the needle valve will cause the blade 15 to ream the solid material from the nozzle, thus restoring the nozzle to operative condition.

- 10 From the mixing chamber 2, fuel passes into the fuel chamber 16, which is integral with the mixing chamber and which is in communication with the mixing chamber throughout its length. The fuel from the 15 mixing chamber also passes to a second fuel chamber 17, which is spaced from the fuel chamber 16 and arranged in side-by-side relation therewith. The mixing chamber 2 is provided at the end remote from the wall 3 with a pocket 18 into the side wall of which 20 is screwed a large fuel conducting pipe 19 which is secured to and in communication with the fuel chamber 17. By rotating the fuel chamber 17 about the axis of the pipe 19, the spacing of the two fuel chambers 16 and 25 17 may be varied, thereby permitting the burner to be adjusted to properly fit in any desired installation. The fuel chambers 16 and 17 are preferably provided with lateral 30 fuel release apertures 21 and 22, so that the flames of fuel are directed laterally from the fuel chambers. These apertures are preferably arranged on both sides of each fuel chamber so that eight rows of flames are 35 produced, four of the rows being formed between the two fuel chambers 16 and 17. These two chambers are spaced apart and there is a free air space between them, permitting the free passage of air to the fuel 40 release apertures on the adjacent sides of the fuel chambers to support the combustion of the fuel issuing from these apertures. The side walls of the chambers 16 and 17 are preferably vertical to permit the free 45 access of air to the flames issuing from the apertures. The fuel chambers are also preferably provided with legs 23 for supporting them above the base or supporting element on which they are placed, to permit the free 50 flow of air around the fuel chambers, to provide for perfect combustion of the issuing fuel.
- 55 Each fuel chamber is provided with a top wall 24 having elongated passages therein of less width than the fuel chamber. Arranged on the top wall 24 is a gas release aperture bar 25 having elongated passages 26 therein adapted to register with the elongated passages 27 in the wall 24. The bar 25 is provided with a plurality of spaced 60 teeth 28, these teeth being preferably formed on the top and bottom surfaces of the bar, and these teeth cooperate with the wall 24 and the top plate 29 to form a plurality of 65 gas release apertures 31. Due to the width

of the bar 25 and the plates or walls 24 and 29, and the narrowness of the apertures 26 and 27, the apertures 31 are of considerable depth. On account of this depth, the apertures may be made wide, that is, the teeth 70 may be relatively high, to permit the discharge of a large amount of gas. Due to the depth of the passages, the increased width thereof will not result in backfire into the chamber. Should the passages be made 75 shallow, the width would have to be made very small in order to prevent backfire but by increasing the depth of the passages, the width thereof may also be increased, permitting the discharge of a larger amount of gas, 80 without the liability of backfire. The top plate 29 and the bar 25 and the top wall 24 are secured together and to the fuel chamber by the bolts 32 extending downward through the fuel chamber. The generator 8, in which the liquid fuel is vaporized by the heat produced by the combustion of the vaporized fuel, is preferably placed above and adjacent to the fuel release apertures of one of the fuel chambers, so that the generator 8 85 is out of the path of the flames issuing from the burner. The generator is thus heated by radiant heat only and not by direct contact with the flames. Therefore, the temperature of the generator is kept lower than 90 if it came into direct contact with the flames and as a result carbonization of the fuel in the generator 8 is greatly reduced. Some carbonization will occur, however, and in order to prevent the solid particles from 95 entering the vapor fluid conduit 12, such conduit is provided with an extension 33 which extends upward into the generator 8 to a point adjacent the top thereof so that solid particles accumulating in the generator 8 100 105 will not have a tendency to pass into the tube 12.

The generator is provided at its fuel inlet end with a fuel distributor which operates to control the flow of liquid fuel and to 110 distribute such fuel so that it will not be heated in large masses. This distributor preferably comprises an integral structure consisting of a plurality of spaced metallic discs 34, the discs being integral with the 115 intervening studs. The discs are somewhat smaller in diameter than the interior of the generator tube 8, so that the liquid fuel is permitted to flow past the discs. The distributor is unattached to the generator tube 120 and is held in position therein by a stiff wire 35 which projects from the end of the distributor into contact with an abutment, such as the extension 33, in the tube 8. The tube 8 will in time become fouled with carbon and require cleaning and a large portion of this carbon will form in the spaces between the discs 34 of the distributor. When it is desired to clean the generator 8, the nut 36 at the end thereof is removed, 130

exposing the end of the distributor. At such end, the distributor is provided with a screw socket and a suitable removing tool, such as a screw-eye 38 may be screwed into the socket for the purpose of withdrawing the distributor. In the event that the carbon in the generator has caked and the distributor is held tight, a blow, as by a hammer, on the eye 38 will free the distributor in the tube so that it may be withdrawn. The wire 35 is sufficiently flexible to permit the distributor to move inward under the blow.

For the purpose of initially starting the burner from a cold condition, a trough 37 is provided on the top wall of the mixing chamber 2 and this trough is directly below the generator 8. This trough is usually filled with absorbent material, such as asbestos, and by saturating this material with gasoline or kerosene and igniting the saturated material, sufficient heat is developed to raise the temperature of the generator to a sufficient degree to vaporize the liquid fuel therein and this vapor then passes into the mixing chamber and out of the fuel release apertures, where it is ignited by the flame rising from the saturated material in the trough 37. When the two fuel chambers 16 and 17 are spaced apart a considerable distance, the fuel issuing from the release apertures of the burner 17 may not be ignited by the flames from the burner 16, and to insure the ignition of the fuel being discharged from the burner 17, I have provided a pilot light on the burner 17. This pilot comprises a small trough 38 on the top wall of the fuel chamber 17, which trough is filled with an absorbent material such as asbestos. Before the burner is initially started this absorbent material is saturated with a fuel such as gasoline or kerosene and the fuel is ignited. This fuel burns in the trough 38 until fuel is discharged from the fuel release apertures of the burner and then such discharging fuel is ignited by the flame of the pilot burner.

I claim:

1. In a gaseous fuel burner, a mixing chamber and a pair of longitudinal spaced parallel fuel chambers provided with fuel release apertures, communicating with the mixing chamber, the spacing between said chambers being adjustable to vary the width of the burner.
2. In a gaseous fuel burner, a mixing chamber, a longitudinal fuel chamber provided with fuel release apertures fixed thereon and communicating with the fuel chamber, a second longitudinal fuel chamber provided with fuel release apertures, spaced from said first fuel chamber and means adjustably connecting the second fuel chamber with the mixing chamber, whereby the distance between the two fuel chambers may be varied.

3. In a gaseous fuel burner, a mixing chamber, a longitudinal fuel chamber provided with fuel release apertures, communicating with the mixing chamber, a second longitudinal fuel chamber provided with fuel release apertures, spaced from and disposed in parallel relation to said first fuel chamber in a horizontal plane, there being a clear open space between said fuel chambers to permit the passage of air between said chambers and means connecting the second fuel chamber with the mixing chamber and permitting relative rotation therebetween.

4. In a gaseous fuel burner, a mixing chamber, a longitudinal fuel chamber provided with fuel release apertures, communicating with the mixing chamber, a second longitudinal fuel chamber provided with fuel release apertures, spaced from and disposed in parallel relation to said first fuel chamber, there being a clear open space between said fuel chambers to permit the passage of air between said chambers and means adjustably connecting the second fuel chamber with the mixing chamber, whereby the width of said open space may be varied.

5. In a gaseous fuel burner, an elongated fuel chamber provided with fuel release apertures, a second elongated fuel chamber provided with fuel release apertures, the two chambers being arranged side by side and a connecting pipe secured to one chamber adjacent one end thereof and screwed into the other chamber at the adjacent end thereof, said pipe being entered into the latter chamber for a sufficient distance to permit variation in the spacing of the two chambers without breaking the connection between them.

6. In a gaseous fuel burner, an elongated mixing chamber, an elongated fuel chamber provided with fuel release apertures, formed integral with the mixing chamber and in communication therewith, means for introducing fuel into one end of the mixing chamber, a second elongated fuel chamber provided with fuel release apertures, arranged at the side of and spaced from the first fuel chamber and an adjustable conduit connecting the end of the mixing chamber remote from the fuel introducing means, with the second fuel chamber whereby the distance between said chambers may be varied.

7. In a gaseous fuel burner, a pair of connected fuel chambers, each provided with fuel release apertures, the chambers being spaced apart in side by side relation to permit the passage of air upward between the chambers to the fuel release apertures and legs for supporting the bottoms of the chambers above the element on which they are supported, to permit the free passage of air under the chambers and means for varying the distance between said chambers.

8. In a gaseous fuel burner, a fuel chamber having a narrow, elongated fuel discharge passage in its upper wall, a bar having a longitudinal series of passages therethrough registering with said fuel discharge passage, the spaces between the passages of said series being occupied by transverse bridges, teeth on the upper and lower faces of said bar coinciding with said bridges, the teeth on the lower surface engaging the upper

wall and forming therewith a plurality of fuel release apertures corresponding with the passages of said longitudinal series, and a plate overlying the bar and forming a plurality of fuel release apertures corresponding with the passages of said longitudinal series.

In testimony whereof, I have hereunto set my hand.

JESSE E. KRESKY.
